UNITED STATES PATENT OFFICE.

OTHO R. OVERMYER, OF DETROIT, MICHIGAN, ASSIGNOR TO DODGE BROTHERS, OF DETROIT, MICHIGAN, A CORPORATION OF MICHIGAN.

DESIGN FOR A BACK CURTAIN OF AN AUTOMOBILE-TOP.

51,757.

Specification for Design.

Patented Feb. 12, 1918.

Application filed November 25, 1916. Serial No. 133,504. Term of patent 7 years.

To all whom it may concern:

Be it known that I, OTHO R. OVERMYER, a citizen of the United States, residing at Detroit, Michigan, have invented a new, original, and ornamental Design for Back Curtains of Automobile-Tops, of which the following is a specification, reference being had to the accompanying drawing, forming part thereof.

The figure is an elevation of a back curtain of an automobile top, showing my new design.

Copies of this patent may be obtained for five cents each, by addressing the "Commissioner of Patents, Washington, D. C."

I claim:

The ornamental design for a back curtain of an automobile top as shown.

Signed at Detroit, Michigan, this 22nd day of November, 1916.

OTHO R. OVERMYER.
